SYNCHRONIZING SYSTEM FOR
TELEGRAPHYEugene E. Shenk, Brooklyn, N. Y., assignor to
Radio Corporation of America, a corporation
of Delaware

Application August 25, 1945, Serial No. 612,682

8 Claims. (Cl. 178—66)

1

This invention relates to synchronizing systems for telegraphy, and more particularly to improvements in such systems wherein it becomes possible to derive synchronizing control from frequencies of tone modulations simultaneously used to characterize the marking and spacing elements of code signals.

My invention finds particular utility in radio signalling because it is common practice to tone-modulate the signals for radio transmission. The trend of radio signalling is also one which utilizes more and more the characterization of marking and spacing code elements by means of two distinguishing tone frequencies. This method provides continuous carrier transmission in place of interrupted carrier transmission.

In carrying out my invention I have taken advantage of the fact that the two tones used in signalling may be derived from the same frequency source which determines the speed of transmission of the code elements themselves. The common frequency source at the transmitter is, therefore, fed through two different circuits, one for supplying the marking and spacing tone frequencies, and the other for controlling the frequency of an alternating current which in turn is used for purposes of synchronizing a distributor. At the receiving station the two-tone audio signals are utilized in two ways, one for controlling a relay which operates in accordance with the marking and spacing code elements of the signals, and the other for the purpose of synchronizing the receiving distributor with the transmitting distributor.

It is an object of my invention to provide equipment both at a transmitting station and a receiving station which will meet the requirements of a synchronizing system operating under control of a single frequency source in accordance with the foregoing brief description.

It is another object of my invention to provide improvements in synchronizing systems which will overcome the difficulties in, and objections to, synchronizing devices of the prior art.

Still another object of my invention is to provide an improved synchronizing system of great simplicity and relatively low cost.

Other objects and advantages of my invention will become apparent in the description to follow. This description is accompanied by drawings in which

Fig. 1 shows diagrammatically a preferred arrangement of parts to be utilized at a transmitting station, and

Fig. 2 shows diagrammatically a preferred em-

2

bodiment of equipment to be utilized at a receiving station.

Heretofore the methods of maintaining the receiver speed the same as that of the transmitter have fallen generally into three classes, as follows—

1. Where independent frequency standards were used at both the transmitter and the receiver. These standards were of as high accuracy as it was practical to attain. This permitted operation of the system for a length of time which depended upon the accuracy of the frequency standards. At the end of this time, it was necessary to manually readjust the phase of the receiver with respect to the transmitter.

2. Where independent frequency sources were used at both the transmitter and the receiver and a method was employed of automatically correcting the frequency at the receiving site to coincide with that of the transmitter.

3. Where an additional communication channel was required to send the synchronizing frequency to the receiver.

All three of the above synchronizing methods possess the disadvantages of being clumsy and inconvenient in operation, or uneconomical, or both.

Referring now to Fig. 1 of the drawing, I show therein, partly in block diagram and otherwise in detail, a circuit arrangement having a two-fold purpose, namely, to tone-modulate a train of code signals, and also to supply a control frequency for driving a distributor at a rate which maintains a fixed frequency relation to both the marking and spacing tone frequencies of the signals.

A common frequency source 1 is preferably of the form of an electronic generator. It could, however, be a tuning fork vibrator or any other wave source having a fair degree of constancy. In the majority of applications, however, it is unnecessary that the frequency of this source be maintained within such close tolerances as has been found necessary in synchronizing systems of the prior art.

The output from the frequency source 1 is fed through one path which includes a frequency divider 2 and a wave shaper 3. The purpose of the wave shaper will be explained hereinafter.

The output from the wave shaper 3 is fed into two parallel-connected filters 4 and 5 which respectively pass the mark and space tone frequencies. The output from filter 4 is connected to one contact 6 on a polar relay 8. The output from the other filter 5 is connected to con-

55

tact 7 of this same polar relay. The tongue 9 of the relay may be conventionally connected to the modulator of a radio transmitter. For alternative applications, however, the mark and space frequencies may be utilized in any well known manner. For example, they may be transmitted over a wire line without the aid of a carrier wave.

Relay 8 is controlled by any conventional code keying device, such as a tape transmitter. One or several such transmitters may be employed depending upon whether the signals are to be transmitted over a simplex channel or whether time division multiplex channels are provided.

As shown in Fig. 1 a rotary distributor 10 comprises a segmented ring having eighteen segments 11 and a solid collector ring 12. The individual segments 11 are connected respectively to keying contacts of three different tape transmitters, if such are to be used. Other code element keying devices may, however, be employed, as is conventional in the telegraph art. The distributor 10 is shown having segments 11 sufficient for the multiplex transmission of 6-unit code signals on each of three different channels I, II, and III. Alternatively a distributor may be employed which has any required number of segments suitable for simplex operation as well as for multiplexing any number of channels and suitable furthermore for the transmission of code signals having five or more code elements. The essence of my invention is, therefore, independent of the design of the distributor. In fact, it is contemplated that in certain applications a rotary distributor would be dispensed with and an electronic distributor would be substituted.

The utilization circuit on the output side of the frequency source 1 has a second branch indicated by the conductor 120 which leads to a frequency divider 14 and thence to a wave shaper 15. In certain instances the frequency divider 14 may be dispensed with and the wave shaper 15 may have its input circuit coupled to the output side of the frequency divider 2. The question of whether the frequency divider 2 may or may not be sufficient is determined by the ratio to be chosen between the signalling tone frequencies and the frequency of an alternating current to be used for energizing a synchronous motor 17 which drives the distributor 10. Preferably, however, the synchronizing frequency will be lower than either of the signalling tone frequencies. It is to be understood, therefore, that the frequency divider units 2 and 14 may be such as to develop output frequencies suitable for their respective utilization requirements. The frequency division may also be obtained in one or a plurality of stages according to the convenience and design economy of electronic devices within the divider units.

The purpose of the wave shapers 3 and 15 is to improve the sign wave characteristics of the output from the respective frequency dividers 2 and 14 and to suppress unwanted harmonics as far as possible. The wave shaper 3, however, must pass two harmonics of the output from the frequency divider 2 and is, therefore, so designed as to favor the particular harmonics which are chosen to represent the mark and space frequencies. In the case of the wave shaper 15 a single frequency of output is desired and this frequency is one which is selected for amplification in any amplifier unit 16 from which energy is obtained to drive the synchronous motor 17. This motor is connected to the shaft of the distributor on which a brush arm 18 is mounted. The brush arm

carries brushes 13 which wipe over the segments 11 and the solid ring 12 so as to successively collect the signal pulses of positive and negative polarity and to apply the same for purposes of controlling the operation of the polar relay 8.

From the foregoing description of Fig. 1 it will be seen that a constant frequency relationship is maintained between the rate of transmission of the code signals and the frequencies of the marking and spacing tones which are used to characterize the code signals. In the description of Fig. 2 to follow it will also be observed that the frequencies of the marking and spacing code elements are themselves capable of utilization for purposes of synchronizing the receiving distributor with the synchronous speed of the transmitting distributor.

Referring now to Fig. 2 I show therein a filter 20 the purpose of which is to improve the signal-to-noise ratio and pass the two-tone audio signals which may be derived from any conventional receiving unit. The output from the filter 20 is fed to an amplifier and limiter unit 21 which in turn delivers an output across a coupling capacitor 22 to a branched circuit in the respective arms of which are three resistors 23, 24 and 25. The branches containing resistors 23 and 24 will first be described as portions of the apparatus for translation of the code signals.

A twin diode discharge tube 26 has its electrodes suitably connected to input and output circuits so that pulses of one polarity are derived from the marking frequency, and pulses of opposite polarity are derived from the spacing frequency. Thus one cathode 27 and one anode 30 are connected to the input circuit while the other cathode 29 and the other anode 28 are connected to the output circuit. A tank circuit f_s is adjusted to resonate with the spacing tone frequency. Another tank circuit f_m is adjusted to resonate with the marking tone frequency. One terminal of each tank circuit is grounded.

The marking tone frequency f_m upon being rectified across the space path between cathode 27 and anode 28 traverses an output circuit resistor 31 and thus biases to cut-off a grid 36 in tube 32 of a conventional locking circuit. Tube 32 and tube 33 are so associated in this locking circuit as to produce a rectangular wave the peaks of which represent marking elements and the valleys of which represent spacing code elements.

The rectification of the spacing frequency f_s takes place across the rectifier electrodes 29 and 30 in the twin diode tube 26. The polarity of these rectified pulses is such that when they traverse the resistor 31 the grid 36 in the locking circuit tube 32 is positively biased and renders this tube conductive.

Capacitors 34 are connected respectively to the two branches of the output circuit from tube 26 and are used for grounding the ripple component of the tone frequencies, thus smoothing out the pulses as delivered to the control grid 36 of tube 32. Capacitor 35 is connected between this grid and ground and serves further for smoothing purposes.

The details of the locking circuit comprising tubes 32 and 33 are well known and need not, therefore, be further described herein. The output may be taken off of either one of the anodes in the tubes 32 and 33, but it is here shown that this output is conducted through a resistor 37 to the control grid in an amplifier tube 38. The connections for tube 38 are also conventional and while this tube is shown as a pentode, other types

of amplifier tubes may, of course, be chosen. The anode circuit for tube 38 may be traced from a source of D. C. anode potential the positive terminal +B of which is connected to a common conductor 40 leading to as many selector magnets as may be required in one or a plurality of printers or other code translating devices. The individual circuits for the printer selector magnets are shown connected respectively to different segments 41 of a rotary distributor. In the specific embodiment herein illustrated these segments are eighteen in number and may be grouped as for 3-channel multiplex reception. The respective groups are labeled Channel I, Channel II and Channel III, each having six conductors which represent the units of a 6-unit code. A collector ring 42 is connected to the anode in tube 38. The distributor brush 39 completes the anode circuit through tube 38 and successively through the printer magnets, the latter being selected for energization whenever tube 38 is rendered conductive. A voltage divider comprising resistor sections 71, 72 and 73 is connected across the terminals of the D. C. source, the negative terminal being grounded. The screen grid of tube 38 is connected to the junction between resistors 71 and 72. The cathode is connected to the junction between resistors 72 and 73. The ohmic values of these resistors 71, 72 and 73 are such that tube 38 is normally non-conducting but may be rendered conductive by a positive pulse applied to its grid through resistor 37.

From the foregoing description of the receiving circuit it will be observed that the incoming signal elements are distinguished by their frequencies f_m and f_s representing marking and spacing units respectively. The signals are, therefore, subjected to rectification in the twin diode rectifier tube 26, the output from which is utilized in controlling the locking circuit in which tubes 32 and 33 are disposed. The signals are then delivered by the locking circuit to the amplifier tube 38, the output from which is fed through the distributor to the selector magnets in succession. The magnets are selectively actuated only when tube 38 is rendered conductive.

I shall now describe the portion of Fig. 2 which relates to synchronizing control of the receiving distributor 44.

It was previously stated that the output from the amplifier and limiter unit 21 is to be fed across coupling capacitor 22 to three branches, of which the branches containing resistors 23 and 24 are related to the code signal translator. The branch containing resistor 25 is used solely for purposes of synchronizing the distributor 44.

The tone signal potentials flowing through resistors 25 and 52 to ground are utilized in the control of a twin triode limiting amplifier tube 45. The purpose of this tube is to exercise synchronizing control over the operation of a multivibrator tube 75 which is also of the twin triode type. The circuit components of these tubes 45 and 75 will first be described, after which their operation in a preferred embodiment will be set forth specifically by way of example.

In tube 45 a space path *a* is defined by a cathode 46 and an anode 48, a control grid 47 being interposed. Likewise, the space path *b* is defined by a cathode 49 and an anode 51, a control grid 50 being interposed. Resistor 52 interconnects the control grid 47 and ground. Resistor 54 interconnects the cathode 46 and ground. Capacitor 55 is in shunt with resistor 54.

Resistor 53 interconnects the control grid 50, 75 of tube 75.

and the cathode 49, which cathode is directly grounded. Anode potential from the source indicated as +B is fed through resistor 56 to the anode 48 and through resistor 57 to the anode 51. Control grid 50 is coupled to the anode 48 through a capacitor 58.

The multivibrator tube 75 possesses two space paths *c* and *d*, space path *c* being defined by cathode 76 and anode 78, between which a control grid 77 is interposed. The space path *d* is defined by cathode 79 and anode 81, between which a control grid 80 is interposed. The control grid 77 is connected to the grounded cathode 76 through a resistor 82. The control grid 80 is connected to ground through a resistor 84. The cathode 79 is also connected to ground through a potentiometer 63 in series with a resistor 83. Anode potential is supplied from the +B source terminal to anode 78 through a potentiometer 60, and to anode 81 through a resistor 61.

Between the anode 78 of space path *c* and the control grid 80 of space path *d* a cross coupling capacitor 85 is connected. Between the anode 81 of space path *d* and the control grid 77 of space path *c* a cross coupling capacitor 86 is connected.

It is well known that the circuit constants of a multivibrator may be so adjusted that it will act as a frequency divider under control of trains of impulses used to build up a certain charge on a time constant circuit. The triggering action may thus be made such that the rectangular wave output will be a certain sub-harmonic of the input frequency. In the arrangement of my invention, however, it is desired that the output frequency be maintained constant while it is locked in step with either one of the higher tone frequencies used as mark and space signal components. I, therefore, provide two time constant circuits for transferring control from tube 45 to tube 75. One of these time constant circuits comprises a capacitor 59 and a portion of the potentiometer 60, these elements being connected between the anodes 48 and 78 in the two tubes respectively. The other time constant circuit is connected between the anode 51 in the tube 45 and the cathode 79 in tube 75 and includes capacitor 62 in series with a portion of the potentiometer 63.

Now I shall describe the operation of tubes 45 and 75. Their purpose is to fulfill the requirements of a synchronizing system. The rectangular wave output from the multivibrator tube 75 is of substantially constant frequency and is, therefore, suitable for control purposes in developing an alternating current such as may be used in driving a synchronous motor connected to a telegraph distributor or other receiving apparatus to be synchronized.

The circuit constants of the multivibrator tube 75 are so adjusted that the tube will deliver one particular output frequency under synchronizing control of either one or the other of the tone signalling frequencies. That is to say, the output frequency from tube 75 is one sub-harmonic of the marking frequency and another sub-harmonic of the spacing frequency. Thus on one side the control pulses are derived from changes in the conductive state through the space path *a* in tube 45, these pulses being transferred through a time constant circuit which includes capacitor 59 and a portion of the potentiometer 60, thus influencing the anode voltage applied to the anode 78 in the space path *c*.

In the case of applying control pulses for the tripping action in space path d of tube 75 a relatively longer time constant value is assigned to the elements 57, 62 and 63 connected between the anode 51 and the cathode 19 of the tubes 45 and 75 respectively. This value is such that the marking pulses will produce cathode bias potentials of one value and the spacing pulses will produce cathode biasing pulses of a different value. These pulses are, therefore, varied in amplitude so as to produce a different factor of division in one case than in the other. Since, however, the tripping action is to be maintained constant, the two ratios of division will be made to result in the same output frequency from the tube 75.

More generally stated, the multivibrator tube 75 and its related circuits constitute a frequency changer which accepts marking tone frequency f_m and divides it by an integer m ; or it accepts the spacing tone frequency f_s and divides it by a different integer s . The relation between f_m and m , also the relation between f_s and s , is such that

$$\frac{f_m}{m} = \frac{f_s}{s}$$

Therefore, the output frequency obtained from tube 75 is independent of the tone frequency being received.

Capacitor 64 couples the output from tube 75 to the input side of a frequency divided unit 65. Any suitable frequency may be delivered as output from this unit. Such a frequency may, for example, be 60 cycles. A wave shaper 66 delivers sine wave output, say of 60-cycle frequency to an amplifier 67. The output from this amplifier unit is then connected to a synchronous motor 68 whose shaft is coupled mechanically to the rotor of the receiving distributor 44. On this rotor brushes 39 are mounted for commutation purposes.

In place of the electronic circuit arrangement shown in Fig. 2, particularly that part which comprises tubes 45 and 75, I may, of course, resort to other means for translating the two-tone signals into an alternating current of substantially constant frequency suitable for driving the motor 68. For example, if frequency divider circuits are used whose counts are normally independent of the input frequency, then a controlling voltage may be obtained from the locking circuit (tubes 32 and 33), or from the subsequent stage 38, and this voltage may be applied to the frequency changer to produce one factor of division during a marking signal and another factor of division during a spacing signal. Frequency divided circuits are well known in the art which are capable of dividing the input frequency by different factors depending upon the application of a varied D.-C. bias potential to a suitable tube electrode. If a magnetic relay is used in place of the relay tube 38 a pair of contacts may be operated by this relay for applying the control voltage to the frequency divider.

It will now be apparent that the frequency source 1 at the transmitting station need not necessarily be either highly accurate or extremely stable in frequency. This follows from the fact that both the transmitting and receiving distributors are controlled in speed from the same source 1. This desirable operation is obtained without the usual types of phase correction equipment wherein a variable D.-C. controlling voltage is utilized. In such equipment the polarity

and magnitude of the controlling voltage depends upon the sense and magnitude of the frequency difference between the transmitter and the receiver. But the methods of comparing the cyclic rates of the distributors at the transmitter and receiver respectively have in the past been inaccurate and rather undependable, due to the distortion of code signals as transmitted through the ether path between stations. Such difficulties are avoided by the practice of my invention.

I claim:

1. The method of synchronizing a signal receiver with respect to a transmitter, which comprises generating an alternating potential from which two distinct tone frequencies may be derived by frequency division, so characterizing the marking and spacing elements of the signals that they are represented by one and the other of said tone frequencies respectively, deriving from said alternating potential by frequency division a third or synchronizing frequency capable of use at the transmitter for the purpose of channel time separation of the signals, and deriving from said marking and spacing tone frequencies as received the same synchronizing frequency as aforesaid, but capable of use at the receiver for the purpose of cyclic distribution of the signal elements into different translating channels.

2. In a telegraph system having a transmitter equipped to send code signals at a constant rate of code elements per second, and having a receiver including a code element distributor for allocating successive code elements to different translating units, a single frequency source at the transmitter, means for deriving from said source two modulation frequencies useful for characterizing the mark and space elements of the code signals, a frequency divider having its input circuit coupled to said source and having utilization means coupled to its output circuit for driving the transmitter distributor, means at the receiver for producing modulation frequency responses to incoming code signals, a local alternating current source for driving said receiving distributor and means for maintaining constant the frequency ratios between said local source and each of said modulation frequencies.

3. A transmitting station including an alternating current generator, means for obtaining from the output of said generator a plurality of sub-harmonic frequency derivatives, a relay operable to transmit one of said derivatives as a mark signal and a second of said derivatives as a space signal, a distributor for so controlling said relay as to provide channel time separation of said mark and space signals, and means coupled to and controlled by said alternating current generator for driving said distributor at a speed which bears a constant ratio to the frequency of said generator and which speed bears a predetermined frequency relation to the sub-harmonic frequency derivatives constituting said mark and space signals.

4. A transmitting station according to claim 3 and including in the first said means a frequency divider unit, a wave shaper unit and filters individually adapted to pass one and the other of said sub-harmonic frequency derivatives.

5. A receiving station including means for discriminating between one and a second of two characteristic frequencies used as tone modulations in the transmission of code signals, a locking circuit operable in response to transitions from one to another of said frequencies, circuit means under control of said locking circuit and including

contacts of a receiving distributor for allocating the marking and spacing code elements cyclically to different translating units, and means subject to control by derivatives from both of said tone modulations for producing an alternating current of fixed frequency which bears different fixed ratios to the respective modulation frequencies for driving said distributor in synchronous relation to the code element signalling speed.

6. A receiving station according to claim 5 and including in said discriminating means a twin diode discharge tube one space path in which is arranged to rectify a signal component of one modulation frequency and the other space path in which is arranged to rectify a signal component of the other modulation frequency, and connections between said discharge tube and said locking circuit such that flip-flop control of the latter is obtained in response to transitions between the rectification of one modulation frequency and the other.

7. A receiving station according to claim 5 and including a multivibrator circuit for obtaining said alternating current of fixed frequency, said multivibrator having input circuits including time constant components operable to produce frequency division by one factor in the presence of one of said tone modulation frequencies, and by

a different factor in the presence of the other modulation frequency.

8. In a transmitting station equipped to send code signals at a constant rate of code elements per second, a single frequency source, means for deriving from said source distinct modulation frequencies useful for characterizing the elements of said code signals, a switching device coupled to said means for receiving said modulation frequencies and arranged to deliver any one of said frequencies to its output circuit, a distributor linked to said switching device for actuating the same in accordance with the arrangement of the elements of a code character under consideration, and a frequency divider having its input circuit coupled to said source and having utilization means connected to its output circuit for driving said distributor.
